UNITED STATES PATENT OFFICE.

LOUIS GARWITT, OF NEW YORK, N. Y.

GARMENT.

Application filed June 1, 1921. Serial No. 474,039.

To all whom it may concern:

Be it known that I, LOUIS GARWITT, a citizen of the United States, and resident of the city of New York, borough of Manhattan, county of New York, and State of New York, have invented a new and Improved Garment, of which the following is a full, clear, and exact description.

My invention relates to a garment and aims to provide certain new and useful improvements in connection with an article of this character.

In connection with garments and more particularly such garments as are knitted, and are consequently liable to stretch, it is a well appreciated fact that the shoulder portions of the garment become stretched to such an extent as to render the garment unsightly.

20 This is to be predicated to the fact that the upper edges of the sleeves are attached to the body of the garment, and upon the arms of the wearer being inserted through these sleeves the shoulder portions of the 25 body part of the garment are stretched each time.

With this in mind my present invention aims to provide a garment which may be readily and economically manufactured, and 30 is particularly intended for use in connection with knitted articles such as sweaters, although it is not necessarily limited to this adaptation, and by means of which the stretching tendency of the shoulder portions 35 will be reduced to a minimum.

Further objects of my invention will become apparent from the annexed specification taken in connection with the drawings, which latter illustrate one practical embodiment of the same, and in which;

Figure 1 is a perspective view of a garment embodying my improved construction, and

Fig. 2 illustrates in detail the different 45 parts of the garment and their relative positions to each other.

It will be seen in Figure 1 that the reference numeral 5 indicates the body of the wearer to which is applied a sweater 6 of 50 any desirable style and material, preferably knitted, which sweater provides in the usual manner, sleeves 7 attached to the body of the same.

Reference being had to Figure 2 it will 55 be seen that contrary to the conventional construction however, that the back and

front portions 8 and 9 respectively preferably terminate at a point short of each other so that a space is provided, and extending into this space and completely filling the 60 same is a shoulder strip or extension 10 forming a continuation and an integral part of the sleeve 7, all of the parts being secured one to the other, and to the collar 11 in any well known manner, such as by knitting, 65 crocheting or by the usual plain thread stitch.

As clearly shown in the drawing the extension or shoulder strip 10 has two straight side edges 12 and 13 and a straight top edge 70 14. The back panel 8 is provided with a straight upper edge 15 and an inner edge 16 while the front panel 9 is likewise provided with a straight upper edge 17 and an inner edge 18. The edges 14, 16 and 18 are 75 placed in alignment while the edge 19 of the collar 11 is placed in an adjacent and abutting position along the aligned edges 14, 16 and 18. In assembling the garment parts as shown in Fig. 2 the edge 19 of 80 the collar 11 is connected to the edges 14, 16 and 18, the edge 15 is connected to the edge 13 and the edge 12 is connected to the edge 17. The curved edges 20 and 21 of the sleeve 7 are connected to the edges 22 and 85 23 respectively of the panels 8 and 9 while the edges 24 and 25 are connected to each other in order to form the completed sleeve.

As clearly shown in Fig. 1 the garment and sleeves are formed of knitted material 90 with the wales, ribs or rows of knitting in the sleeve, the front and back panels and in the extension 10 running in a vertical direction of the garment but with the wales of the extension 10 at right angles or transversely to the wales of the back and front panels. As the greatest stretch of a knitted fabric is at an angle to the direction of the wales this relative positioning of the wales in the extension and panels is highly important in that the material of the extension 10 will stretch in accommodation to a downward pull on the front and back panels and will stretch only to a small degree in answer to a downward pull on the sleeve 7 caused 100 by the frequent insertion of the wearer's arm. Very little downward pull is placed on the front and back panels by the wearer but frequent downward pull is placed on the sleeves. Hence the garment will accommodate itself to the ordinary uses of the wearer and at the same time remain neat 105 110

and undistorted at the shoulder portion though made of knitted material.

Only one side of the garment has been described as the other side will be formed 5 in substantially the same manner.

It will be appreciated that my invention is not necessarily limited to the specific details shown and described but that various changes of application and structure may be 10 resorted to without departing from the scope of the claim.

I claim—

A sweater comprising front and back panels of knit material each having a substantially straight upper edge adapted to extend 15 approximately from the outer edge of the wearer's shoulder to a point adjacent the

neck of the wearer and each having an inner edge, a sleeve member having an integral shoulder extension of knit material, 20 said shoulder extension adapted to extend approximately from the outer edge of the wearer's shoulder to a point adjacent the neck of the wearer and having substantially straight side edges and a substantially straight top edge, means connecting the said upper edges of said panels to the said side edges of said shoulder extension, the ribs of said shoulder extension being positioned 25 transversely to the ribs of said front and back panels and the said inner edges of the said panels being in substantial alignment with the said top edge of said extension.

LOUIS GARWITT.
